(57) CLAIM

The ornamental design for a hand guard, as shown and described.

DESCRIPTION

FIG. 1 is a front side elevational view of a hand guard shown in position on a rifle embodying the invention, the rear side elevational view being a mirror image of the front side elevational view presented.

FIG. 2 is a front side elevational view of a hand guard embodying the invention, the rear side elevational view being a mirror image of the front side elevational view presented.

FIG. 3 is a left side elevational view of the hand guard embodying the invention.

FIG. 4 is a right side elevational view of the hand guard embodying the invention.

FIG. 5 is a top elevational view of a hand guard embodying the invention; and,

FIG. 6 is a bottom elevational view of a hand guard embodying the invention.
